UNITED STATES PATENT OFFICE

FRANK H. KREUTER, OF PHILADELPHIA, PENNSYLVANIA

JUICE EXTRACTOR

Application filed April 25, 1928. Serial No. 272,816.

The object of this invention is to provide an article especially adapted for individual use at the table and designed to permit of the convenient extraction or pressing of the juice from sliced lemon or the like, without soiling the fingers, and without other unpleasant results.

A further object is to provide a device adapted to be made from a single sheet of metal, with portions thereof pressed out by dies or otherwise, for forming engaging portions, oppositely located when the plate is bent into U form, and portions forming hand or finger members.

With the foregoing and other objects in view, the invention consists in the novel construction and arrangement of elements described, illustrated and claimed, it being understood that modifications may be made within the scope of the claim without departing from the spirit of the invention.

In the drawings forming part of this application:—

Figure 1 shows the device in vertical section, with one side element in elevation, the section being on line 1—1 of Figure 2.

Figure 2 is a transverse section on line 2—2 of Figure 1.

Figure 3 shows the blank before bending into U form, but after having been pressed into shape by dies.

Figure 4 is a perspective view of the completed device.

Referring to Figure 3, the blank may be of about the form therein illustrated, being approximately hexagonal but having certain of the sides curved, as shown at the upper and lower edges as they appear in that view.

The plate includes the portions 10 and 11 adapted to be folded or bent into U form along the central transverse line 12, in order to form a U shaped or V shaped portion 13, as illustrated in Figures 2 and 4.

In subjecting the plate to dies, I form a plurality of series of teeth or projecting elements of any suitable type, these being designated 14 and 15, or the series being so designated, and these elements may project in the form of rectangular devices although any suitable configuration will serve the purpose.

The finger members or hand holds are represented by opposite edge portions 16 and 17, and each is provided with a depression such as 18, the plates including a shoulder adjacent to each depression and the shoulder being designated 19. This permits of properly positioning the fingers with reference to the side elements of the pressure device or extracting device, and further prevents the juices from being ejected upwardly under pressure.

Having described the invention what is claimed is:—

In a device of the class described, a plurality of side members connected along one edge by a fold, approximately parallel series of oppositely projecting elements carried by the side members and constituting pressure devices, and shoulders formed between the projecting elements and those edge portions of the side members remote from the fold, the shoulders being reversely positioned, alined transversely, and each positioned to directly engage the edge portion of an article of fruit placed between the side members.

In testimony whereof I affix my signature.

FRANK H. KREUTER.
